(57) **CLAIM**

We claim the ornamental design for a pavilion, as shown and described.

DESCRIPTION

FIG. 1 is an isometric view of our design for a pavilion; FIG. 2 is a right side view of the design for the pavilion shown in FIG. 1, the left side view being a mirror thereof; FIG. 3 is a front view of the design for the pavilion shown in FIG. 1;

FIG. 4 is a rear view of the design for the pavilion shown in FIG. 1;

FIG. 5 is a top view of the design for the pavilion shown in FIG. 1; and,

FIG. 6 is a bottom view of the design for the pavilion shown in FIG. 1.

The broken lines having shorter consistent dash lengths (dash-dash-dash) shown in the figures depict portions of the pavilion that form no part of the claimed design. The broken lines having longer consistent dash lengths (dash-dash-dash) shown in the figures represent boundaries that form no part of the claimed design.
